(57) **CLAIM**

I claim, the ornamental design for a display with animated graphic user interface, as shown and described.

DESCRIPTION

FIG. 1 is a front view of the first image in a sequence for a display with graphic user interface (GUI) showing my new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the eighth image thereof;

FIG. 10 the eighth image thereof;

FIG. 11 the eighth image thereof;

FIG. 12 the eighth image thereof;

FIG. 13 the eighth image thereof;

FIG. 14 the eighth image thereof;

FIG. 15 the eighth image thereof;

FIG. 16 is the eighth image thereof;

FIG. 17 is the eighth image thereof;

FIG. 18 the eighth image thereof;

FIG. 19 the eighth image thereof;

FIG. 20 the eighth image thereof;

FIG. 21 is the eighth image thereof;

FIG. 22 is the eighth image thereof; and

FIG. 23 is the eighth image thereof; and,

FIG. 24 is a front view of the display with animated graphic user interface, shown separately to illustrate the claimed design in a landscape orientation. The alternative positioning of the GUI in the FIG. 24 drawing forms no part of the claimed design.

The appearance of the transitional image sequentially transitions between the images shown in FIGS. 1 through 23. The subject matter of this patent includes a process or period in which an image changes into another image. This process or period forms no part of the claimed design. The dash-dash broken lines shown in the figures, illustrate the boundary of the claimed design, the dash-dot-dot-dash broken lines in the Figures, illustrate the borders of the display screen and the remaining broken lines illustrate portions of the animated graphic user interface. None of the broken lines form part of the claimed design.
